UNITED STATES PATENT OFFICE.

DANIEL D. WOLFE, OF WASHINGTON, DISTRICT OF COLUMBIA, ASSIGNOR OF ONE-HALF TO HARRY COHEN, OF WASHINGTON, DISTRICT OF COLUMBIA.

SHOE-SHINING PARLOR.

1,421,646.

Specification of Letters Patent.

Patented July 4, 1922.

Application filed March 8, 1921. Serial No. 450,713.

To all whom it may concern:

Be it known that I, DANIEL D. WOLFE, a citizen of the United States, residing at the city of Washington, in the District of Columbia, have invented new and useful Improvements in Shoe-Shining Parlors, of which the following is a specification.

This invention relates to the construction of shoe-shining parlors, and it comprises an arrangement wherein a passage is provided, an elevated platform arranged beside said passage, a plurality of seats arranged on said platform, foot rests disposed at the front of said platform in alinement with said seats, a passage arranged on the top of said platform and behind the seats, and steps arranged at each end of said platform.

In the present arrangement of shoe shining parlors a comparatively long, narrow room is provided. A number of seats are arranged along one of the side walls of the room, the seats being arranged at an elevation for the convenience of the operators. Foot rests are arranged in front of these seats suitably elevated from the floor. An aisle or passage extends from the front of the stand to the opposite wall and this passage must be used by patrons, traveling in both directions, into and out of the shop.

This arrangement is open to several objections. The single narrow aisle provided makes it disagreeable and inconvenient for people entering and leaving at the same time, as there is scarcely sufficient room for them to pass each other. In addition the arrangement of the seats and shoe rests at an elevation for the convenience of the operator makes it necessary to provide steps in front of the seat for the patrons to reach

them, and the foot rests must be placed on these steps. It is inconvenient for the patron to climb over the foot rests in reaching the seats, and extremely so where necessary to mount steps at the same time. This frequently causes the patron's clothing to become caught in the foot-rest and torn.

In the present invention, I have provided means for mounting the platform at one end thereof and separate means removed from

said first mentioned means for leaving the

platform, in order to obviate the necessity for patrons passing each other in mounting and leaving the platform, thus eliminating one of the disadvantages of the old system. I further provide steps for reaching the seats removed from the foot rests, and the patron may proceed to the raised platform without liability of falling over the foot rests or having his clothing caught thereby. After reaching the platform the patron proceeds by the aisle or passage at the back to a vacant chair, and thus reaches his seat without climbing over the foot rests. Revolving chairs may be employed so that the patrons may enter the seats from the rear and swing around to face the foot rests.

In the accompanying drawings, I have shown one embodiment of the invention.

In this showing:

Figure I is a plan view

Figure II is a side elevation, and

Figure III is a front elevation.

Referring to the drawings, the reference numeral 1 designates an entrance aisle or passage where the patron enters the shop. This aisle extends from the front of the room to the rear. A flight of steps 2 are provided at the rear to permit the patron to reach the platform 3. The platform may be made of any suitable material, and is arranged at a suitable elevation to arrange the foot rests at the desired height. An aisle or passage 4 is arranged at the back of the platform. Foot rests 5, arranged in pairs and suitably spaced from each other are arranged on the platform adjacent the aisle or passage 1. The foot rests are arranged on suitable supports 6 secured to the platform in any suitable manner.

Chairs 6 are arranged on the platform between the aisle and the front rests, the chairs being arranged in alinement with each pair of foot rests. As shown revolving chairs may be employed. The base 7 is adapted to receive a stem 8 secured to the seat 9 of the chair, whereby the seat may be revolved to face the aisle or the foot rests. A second flight of steps 10 are arranged at the front of the platform to permit descent of the patron when leaving.

As shown the front of the platform is in the form of a vertical wall 11, and this wall may be provided with openings 12 for the reception of polish, brushes, and other material or apparatus.

A patron entering the shop proceeds by the passage 1 to the rear, and ascends the steps 2 to the platform 3. The patron then travels along the aisle or passage 4 to a vacant chair, which may be revolved to face the aisle and then revolved to face the foot rests 5 arranged in front of the chair. When leaving the patron walks along passage 4 to the front steps 10, and then descends thus arriving at the exit.

It will be apparent that the provision of an entrance passage or aisle 1, and an exit passage 4 eliminates the inconvenience of passing persons in the narrow aisles provided, as the direction of travel in either aisle is always the same, one aisle being used for moving to the rear of the room and the other for moving to the front.

In actual practice, the aisle 4 may be employed for traveling toward the rear of the room, and the aisle 1 as an exit. In this case, the steps 10 are used for ascending the platform, and steps 2 for descending. Either method may be employed the function of the two aisles being to prevent necessity of passing people traveling in the opposite direction. It is obvious that the aisle 1 may be dispensed with as a passage for patrons and used only by the employees of the shoe-shining parlor in which case suitable provision may be made for mounting and leaving the platform by stairways spaced at a substantial distance from each other so that patrons may mount the stand at one point and leave without returning to said point.

The provision of steps at each end of the platform, removed from the foot rests permits the patron to reach the seats in an orderly manner without climbing over the foot rests. This prevents the possibility of tearing clothing in reaching the seats, which frequently happens in the present type of stand where it is necessary to pass the foot rests, while ascending the steps to reach the seats.

While I have shown and described one embodiment of the invention, it is to be understood that various changes may be resorted to in the details of construction without departing from the spirit of the invention.

What I claim is:—

1. A shoe shining parlor comprising a passage, a second passage, said passages being connected, a platform arranged between said passages, seats on said platform, said second passage comprising an aisle on the top of said platform behind said seats and the connections between said passages comprising stairways spaced at a substantial distance from each other.

2. A shoe shining parlor comprising an elevated platform, an aisle arranged in the rear of the platform, a second aisle arranged in front of and below the platform, steps connecting the ends of the two aisles, and seats arranged on said platform.

3. A shoe shining stand comprising an elevated platform, an aisle arranged in the rear of the platform, an aisle in front of and below said platform, and steps arranged at each end of said aisles.

4. A shoe shining stand comprising an entrance aisle and an exit aisle, one of said aisles being arranged at an elevation, a platform arranged between said aisles at substantially the same elevation as the elevated aisle, seats arranged on said platform, and steps connecting said aisles.

5. A shoe shining stand comprising an elevated platform, an aisle arranged in the rear of said platform, an aisle arranged in front of and below said platform, steps connecting said aisles, seats arranged on said platform and foot rests arranged in front of said seats adjacent said second aisle.

6. A shoe shining parlor comprising an entrance aisle and an exit aisle, passageways connecting said aisles, a shoe shining stand between said aisles, said stand comprising stairways.

7. A shoe shining parlor comprising an entrance aisle and an exit aisle, said exit aisle being elevated with respect to said entrance aisle, passageways connecting said aisles and a shoe-shining stand between said aisles, said stand comprising an elevated platform on a level with the exit aisle, and revolving chairs on said platform.

8. A shoe shining stand comprising an elevated platform, chairs and foot-~~rests~~ on said platform, said platform being wide enough to provide a passageway on the top thereof behind the chairs, a stairway leading as an entrance to the top of said platform and a separate stairway spaced at a substantial distance from said first mentioned stairway and leading as an exit from the platform.

9. A shoe shining parlor comprising an elevated platform, chairs and foot-~~rests~~ on said platform, a passageway on said platform behind said chairs, an entrance stairway leading to said passageway at one end thereof, and an exit stairway leading from said passageway at the opposite end thereof.

10. A shoe-shining stand comprising an elevated platform, chairs and foot-~~rests~~ mounted on said platform, the top of said platform being wide enough to provide a passage on the top thereof, a stairway leading as an entrance to said passage, and a separate stairway spaced at a substantial distance from said first mentioned stairway and leading as an exit from said passage.

11. A shoe-shining parlor comprising an

elevated platform, chairs and foot-rests on said platform, said platform being wide enough to provide a passageway on the top thereof, a passage-way below the top of said platform, steps leading as an entrance from the lower passage-way to the upper passage-way, and other steps leading as an exit from

the upper passage-way to the lower passage-way, said last mentioned steps being spaced at a substantial distance from said first mentioned steps. 10

In testimony whereof, I affix my signature.

DANIEL D. WOLFE.
